UNITED STATES PATENT OFFICE.

HENRY N. CARRAGHER, OF FALL RIVER, MASSACHUSETTS.

SAFETY LOCK.

Application filed November 23, 1927. Serial No. 235,258.

My invention relates to means for securing the steering wheel to the steering post of a vehicle without the use of keys, the combinations of which are limited only by the 5 number of sections employed and the number of teeth in the operating discs within the same.

It is to be understood that my invention is of broad application and may, for example, 10 be embraced in a door lock.

In the drawings illustrating the principle of my invention, and the best mode known to me of embodying the same in operative structure,

15 Fig. 1 shows my invention housed and attached to the steering post and steering wheel of an automobile, the housing being broken away, the wheel locked;

20 Fig. 1^a is a like view, the wheel unlocked;

Fig. 2 is an enlarged horizontal section of Fig. 1, on line 2—2;

Fig. 3 is a side elevation, the casing being in section;

25 Fig. 4 is a side elevation of the locking bolt;

Fig. 5 is a cross-section on line 5—5, Fig. 3;

30 Fig. 6 is a cross-section on line 6—6, Fig. 3;

Fig. 7 is a cross section on line 7—7, Fig. 3;

35 Fig. 8 is a cross-section, with disc and actuating pawl of Fig. 7 removed;

Fig. 9 is an enlarged cross-section on line 40 9—9, Fig. 3, showing the bolt and disc of one unit in position to be unlocked;

Fig. 10 is an enlarged cross-section, like Fig. 9, except part of the manipulating plate is broken away to show more clearly 45 the disc, here pictured in locking engagement with the lock bolt, and not engaged by the locking dog;

Fig. 11 is an enlarged cross-section of one unit of the locking mechanism;

45 Fig. 12 is like Fig. 5, with twisting locking handle added;

Fig. 13 is a section in plan, showing means for holding the locking-bolt in unlocked position;

50 Fig. 14 is a diagrammatic view, partly in section, showing a way of applying my invention to a door, opening in or out, the combination lock being operated from the outside of the door, while the door bolt may be moved back or released from the inside without disturbing the combination;

Fig. 15 shows, in plan, the normal shape of the unlocked housing;

Fig. 16 is an enlarged cross-sectional view 60 showing the snap-lock for locking and unlocking the housing, to and from its base on the steering post.

The device is positioned on, and attached to, a base 1 secured to the steering post 2 65 of an automobile, a metallic housing 3 enclosing the device.

This device may be said to be made up of a locking-bolt 4, Figs. 2, 3, 4 and 5, one or more combination discs 5, 6, 7, 8, Fig. 3, and mechanism for operating each of the 70 discs and the bolt, to lock and unlock the steering wheel; each disc and its operating mechanism constituting what may be called a unit.

The discs 5, 6, 7, 8 are of uniform size, 75 and are mounted upon a central shaft 9 extending through frame plates or partition walls 10 adjacent to each disc, and form for it, and its operating mechanism, a separate section.

80 As these units are identical in structure, only one of four manipulating members, A, B, C, D, is particularly illustrated and described herein, namely, that which has a manipulating member A.

85 Each disc, for example disc 5, has a toothed circumference, the teeth 11 beginning at a distance from a slot 12 through which the locking-bolt 4 passes, equal to the distance of one tooth from the other, and extending at least two-thirds around the circumference of the disc; one portion, 13, say one-third of the circumference, being left smooth, so that a manipulating member, as A, Fig. 10, for actuating the disc by 90 engaging the teeth of the disc, may be prevented from moving the disc, after a certain number of operations. A series of holes 14, equally spaced near the teeth, one for each tooth, forms the secret of the combination mechanism, which may be arranged by placing, in a manner later to be described, a pin 15 in a certain one of these holes, and providing an abutment 16 on the opposite wall to be engaged by the pin 15 to limit the backward movement of each disc, brought about by a spring 17, secured to the disc and to the wall, to revolve the disc back to locked position, when the disc is released, as will hereinafter be pointed out. Here the abutment 110 16, Fig. 8, the axis of the central shaft 9, and the locking-bolt 4 are in the same ver-

80

85

100

105

110

tical plane, and when the bolt 4 and slot 12, Fig. 9, are in alignment the hole adjacent to the abutment 16 is marked 0', the next 1', the next 2', and so on; and the pin 15 is placed in the hole whose number corresponds to that of the secret combination, say 3'.

The locking-bolt is slideable through these slots 12 in the discs and openings in the partition walls. It has slots 18, Fig. 4, along its under side in which the discs may turn; and a shank 19 upon which a double cam 20, Figs. 3, 6, 12, 13, freely turns; one cam 20' to turn and unlock a snap lock, later to be described, for the housing; and the other cam 21 employed in releasing the discs. Lock slots 22, 23, Fig. 2, are provided in base 1 on the steering post 2 and steering wheel 2^a, into which, when in alignment, the locking-bolt 4 may be longitudinally moved into locking position.

The manipulating member, say A, for moving its respective disc 5 into unlocking position for the bolt 4, has an actuating pawl 24, Figs. 7 and 9, with an operating spring 25, an abutment 26 to limit the motion of the pawl, and a pin 27 to which one end of a spring 28 is attached, to restore the manipulating member A to normal position; the forward end of the member having a cam 29 to engage a pin 30 on a distance holder 31 and cause it, against the action of a spring 32, to disengage a groove 33 in a dog 34, thus permitting the dog to engage the teeth 11 on the circumference of the disc 5 during its locking movement. The distance holder rotates on a pin 35 in the partition wall, the free end of the holder resting against the bottom surface of the dog 34, Fig. 9, when the dog engages the teeth-groove into which, when in proper position, it is forced by a spring.

The dogs provided to hold their respective discs in operative position are rotatably mounted upon a shaft 36, as are finger members 37, for releasing the dogs. These release finger members have extended cam surface arms 38, Fig. 12, operated by cam 21 to cause the free ends of the fingers to press down upon the dogs 34, Figs. 6, 9, 10 and 12, and compel them to move against their springs 39 and away from their respective discs.

The double cam member 20, Figs. 6, 12 and 13, rotates freely on the spindle 19 of the locking-bolt, and is operated by an interlocking and twisting member 40, Fig. 13, rotatably secured to the spindle. A plate 41, Figs. 12, 13, secured to the wall of the outer end compartment has a guiding flange 42 along which the double cam member 20, on the locking-bolt, is moved in and out of position; said flange having a locking shoulder 43 with which said cam member is pulled into engagement by a spring.

In the embodiment herein shown, it has been observed that the manipulating members A, B, C, D, with their respective cooperating discs, dogs, and distance members, are oppositely arranged and operated; and to illustrate their workings, it will be assumed that the "secret" combination of the lock is to be "3-4-1-2"; that is, the manipulator A must be reciprocated three times, the manipulator B must be reciprocated four times; the manipulator C must be reciprocated once; and the manipulator D must be reciprocated twice.

That this may happen, the pin 15 is placed in hole 3' in disc 5; a pin is placed in hole 4' in disc B, not shown; a pin is placed in hole 1' in disc C, not shown; and a pin is placed in hole 2' in disc D, not shown. After the above manipulators are operated, the locking bolt and its respective slots in the discs are in alignment, as appears in Fig. 9, and an outward pull on the handle 40, Figs. 2, 3, 13, will cause the locking end of the bolt to move out of the slot 23, Fig. 2, in the steering wheel and release it; and an inward movement will lock the wheel.

To lock the wheel and post, the wheel being unlocked, the slot in the wheel is moved into line with the bolt, the handle 40, Fig. 2, twisted to the right, disengaging the cam member 20 with the shoulder 43. The bolt 4 is moved longitudinally inwardly into engagement with the slot in the wheel, Fig. 2. The handle is again moved to the right, turning with it on the bolt spindle 19, the cam member 20. This causes the cam 21 to engage the cam surface arms 38 of the finger members 37, pivoted at 36; the extremities of these members engaging the end portions of the free arms of the dogs 34, Fig. 10, turning on their pivots at 36; and disengaging the teeth of their respective discs, which, by reason of their springs, as 17, snap back and are brought to a stop by the engagement of their pins, as 15, with the abutments, as 16, on the partition walls; the discs being free to turn in the lock slots 18 in the bottom of the bolt until the solid portions of the discs are in position to prevent any longitudinal movement of the bolt.

But upon the release of the discs by the dogs moving back against the pressure of their springs, the point of each distance holder 31, pivoted at 35, is forced by the spring 32 up into engagement with the groove 33 in the dog, thereby holding the dog out of engagement with the disc, which, being under the strain of the spring 17, returns to normal position as already explained. The wheel and post are now locked together.

To unlock them, the parts are moved according to the combination "3-4-1-2" in the following manner:

Manipulator A, Fig. 10, is pushed in

thrice; that is, it is pushed in, once against the tension of the spring 28, the dog 24 of the manipulator engaging one tooth on the disc 5, while the inclined face 29 of the manipulator contacts the pin 30 on the distance member 31, forcing it down and away from the dog detent 34, and allowing it, by reason of its spring 39, to snap into the next tooth of the disc 5 brought forward by the push of the manipulator. After this push, the spring 28 restores the manipulator to normal position, the manipulator dog 24 moving back one tooth and engaging it. A second and a third push are given this manipulator, and the disc, dog and springs repeat the above operation, but it will be seen that the distance member 31, Fig. 9, does not engage the dog, and that the disc has been moved so that its bolt slot, 20 and the lock bolt, are in line, and but for the locked position of the other three discs and bolt, the bolt could be withdrawn from the lock slot in the steering wheel.

The combination requires, next, that the manipulator B on the opposite side of the disc shaft 9 be operated four times. This is done by pushing the manipulator B and allowing it to be returned to normal position by its spring four times. The parts in this section are identical with those of the first section, except the pin of this second disc is placed in the hole marked 4', but not shown. The consequence is that four pushes and returns of this manipulator B leave the lock slot of its disc, in line with the bolt, and offer no obstacle to the longitudinal movement of the lock bolt.

What has been said of the first and second manipulators applies to the third and the fourth manipulators C and D; remembering that manipulator C has its pin placed in hole 1' of its disc and manipulator D has its pin in the hole 2' of its disc. By pressing manipulator C once, and then manipulator D twice, the slots in their respective discs are also in line with the bolt, which is now free to be moved out of engagement with the slot in the steering wheel.

That it may be so moved, the pull and twisting handle 40, Fig. 2, on the exposed end of the lock bolt, is grasped and pulled outwardly, thereby unlocking the wheel, and at the same time, permitting the spring 44, Fig. 13, to draw the cam member 20 into engagement with the locking shoulder 43 which thereby holds the bolt in unlocked position for as long a period of time as may be required.

To lock the wheel to the post—to repeat the description—the slot in the wheel is moved into line with the bolt 4, Fig. 2, the handle 40 is moved to the right, disengaging the cam member from the shoulder, and the bolt is moved longitudinally inwardly into engagement with the slot in the wheel.

The handle is again moved to the right, turning with it, on the spindle of the bolt, the cam member 21, Fig. 12, the cam 21 of which, in the manner already explained, engaging the cam surfaces 38 of the unlocking fingers 37 and forcing them, as shown in Fig. 10, to move the release dogs 34 out of engagement with the discs, thereby allowing them to return to locked position, and causing the end portions of the distance members 31 to enter the grooves 33 in the end portions of the dogs, and hold them in such position until the manipulators are again operated to unlock the steering wheel and post.

In order that access to the details of the lock may be easily attained, as for the purpose of changing the combination, the housing 3, Fig. 15, in general plan, may, when not locked to its base 1, be said to be V-shaped, that portion 61 being adjacent to the steering post 2, forming a spring tending to hold the housing in that shape; the adjacent top and front edges of the housing being flanged at 3'.

Cut in the opposite sides of the base, is a lock channel 62, adapted to receive pins 63, on the inside of the bottom portion of the housing, when the sides of the latter are pressed together and assume the closed position, as appears, say, in Figs. 2, 3, 5, 9, 10, 13 and 16; said sides being held closed by a snap-lock 64, reference being had particularly to Fig. 16.

A hook-shaped locking blade 65 is pivoted at its central portion 66, to the inside of the front face 67 of the housing; the shank 68 of the hook, having a lock-slot 69 in its free end-portion, to engage a lock-pin 70 on the inside of the other front face 71 of the housing; while the hook portion 72 of the blade has a cam surface 73, which may be engaged by one arm 20' of the double cam 20, movable on the spindle 19 of locking bolt 4, already described.

A tension-spring 74 tends to hold the locking-blade 65 against an abutment 75 on the inside face of the housing, i. e. in position to cause the lock-slot 69 in the blade, to snap over and engage the pin 70, and lock the housing securely to the base 1, and the steering post 2.

It will be noted, see Fig. 2, that when the locking bolt 4 is in engagement with the steering post, and the twisting member 40 is turned to operate the cam 21, Figs. 6 and 12, to cause the finger-members 37 to release the dogs 34, to release the discs 5, 6, 7, 8, the double-cam 20 is not in the vertical plane of the hook-blade 65, and any twisting of the member 40 has no effect on the blade; but that, only when the locking bolt 4 has been withdrawn from the steering wheel 2, and the cam member 20 has been longitudinally moved into engagement with the locking shoulder 43, as shown in Fig. 13, is said

double cam 20 in position to operate the blade 65; in other words, the unlocking cam 20' for the housing 3 can engage and operate the snap-lock 64 only while the combination lock is unlocked, and the cam and the snap-lock are in the same vertical plane.

Assuming now that the housing 3 is locked to the base 1, and that the bolt 4 has been moved into engagement with the locking-shoulder 43, then, to unlock the housing from its base, screw-buttons on the free ends of the manipulating members A, B, C and D are removed, and the twisting member 40, Figs. 13 and 16, is turned to the right, bringing the cam 20' of the double cam 20 into engagement with the cam surface 73 of the hook 72, as shown in Fig. 5, thereby lifting the shank 68 of the blade and its lock-slot out of engagement with the locking-pin 70; the spring rear portion 61 of the housing causing its front end-portions 67, 71, to spring apart, carrying the pins 63 and the housing 3 away from the lock-channels 62 in the base 1, and freeing the housing for removal; access to the combination details is thus obtained.

To lock the housing to the base 1, the former is so placed that by pressing the sides together, the free end-portions of the manipulating members A, B, C, and D pass through their respective holes in the housing, the pins 63 are moved into the lock-channels 62 in the base 1; at the same time, the cam-surface 76 on the free end of the shank 68, engaging the pin 70, against the tension of the coil-spring 74, which causes the lock-slot 69 in the shank to hook over the pin 70, when the housing has become entirely closed and together; the double cam 20, all the while, being held free from the blade, by the shoulder 43 and the spring 44, Fig. 13.

The housing is now securely closed and locked to the base, and the combination lock rendered inaccessible. By screwing the buttons on the free ends of the manipulating members A, B, C and D, the combination lock may be operated in the manner already described.

In Fig. 14, is shown a modification of my invention, whereby it becomes available for locking a door.

The locking mechanism is placed on the inside of a door 50, and the discs, manipulators, etc. are all operated in the same direction, that is, from the outside of the door, by manipulators A', B', C', D', which protrude therethrough. A push-rod X, operatively connected to the cam, as 21, Fig. 12, is used for the purpose of moving the finger members 38, to disengage the dogs 34 from their respective discs and allow the latter to be restored to locking position, in the slots in the bolt, as 4', Fig. 14.

That this bolt may be moved, after the

"combination" has been carried out, a knob 51, on the outside of the door, is connected with a lever 52, in engagement with the bolt.

On the free end portion of the bolt is mounted a sleeved bolt head 53 to engage a suitable slot 54 in the door frame; a spiral spring 55 always tending to move the bolt head away from the lock bolt. This sleeved head has a longitudinal guide slot 56 in sliding engagement with a guide pin 57 in the bolt; and a finger pull 58, on the inside of the door.

To open the locked door, the manipulators A', B', C', D', are operated to correspond to the "secret combination". The bolt 4' now being slideable in the slots in the discs, the knob 51 is moved to the right, the bolt and bolt head 53 respond, and the door becomes unlocked and may be opened.

To lock the door, shut it, and push the knob X, thereby releasing the discs which snap into the bolt slots and lock the bolt, in a manner already understood.

If the combination lock is closed, then it is possible, if one desires, to open the door from the inside; and this may be done by grasping the finger pull 58, and moving it to the right against the action of the spiral spring 55, the sleeved bolt head 53 sliding on the bolt 4' and becoming disengaged from the door frame, thus freeing the door to be opened.

By means of my invention, I do away with keys necessarily used in other locking structures, to guard against theft, the number of movements of each of the manipulating members being necessarily known to the operator before the device can be operated and the locking-bolt removed from locked position.

This application is a continuation in part of application Serial No. 155,210, filed by me, Dec. 16, 1926, wherein the snap-lock for the housing of the safety lock was mentioned and claimed in combination.

Desiring to protect my invention in the broadest manner legally possible, what I claim is:

1. In a keyless combination lock, a spring-operated disc with teeth along its circumference; a spring-operated dog to engage said teeth, said dog being pivoted, and having in its free end-portion a holding slot; a spring-operated distance-holder, pivoted at end and having a pin in its free end-portion, said portion normally to engage said groove in said dog and hold said dog out of engagement with said teeth, a slideable plate, normally operated in one direction, and a spring to move it in an opposite direction, said plate having a pawl to engage and disengage said teeth and actuate said disc, and a cam-surface in engagement with said pin in said distance-holder to cause said holder to disengage said slot and permit

5 said dog to pass by said member to engage said teeth on said disc; and means to cause said dog, against the action of its spring, to disengage said teeth, the free end-portion 10 of said dog engaging the free end-portion of said distance-holder, forcing it down, and passing by it, so that the free end-portion of the holder may, by the action of its spring, engage said groove in said dog 15 and hold said dog free from said teeth, and allow the spring of said disc to move said disc.

2. In a keyless combination lock, for vehicles and doors, having a lock-bolt, a rotatable disc; a spring tending to restore it to normal position; said disc having a series of teeth along the greater part of its circumference, and a lock-slot in which the lock-bolt may be reciprocated; and said lock-bolt having a lock-slot in which said disc 20 may be moved to hold the bolt in locked position; a spring-operated dog to engage said teeth, said dog being pivoted, and having in its free end-portion a holding-slot; a 25 spring-operated distance-holder, pivoted at end and having a pin in its free end-portion, said portion normally to engage said groove in said dog, and hold said dog out of engagement with said teeth; a slidable plate 30 manually operated in one direction, and a spring to move it in an opposite direction, said plate having a pawl to engage and disengage said teeth and actuate said disc, and a cam-surface in engagement with said 35 pin in said distance-holder to cause said holder to disengage said slot and permit said dog to pass by said holder to engage said teeth on said disc; means to cause said dog, against the action of its spring, to 40 disengage said teeth, the free end-portion of said dog engaging the free end-portion of said distance holder, forcing it down, and passing by it, so that the free end-portion of the distance-holder may, by the action of 45 its spring, engage said groove in said dog and hold said dog free from said teeth, and allow the spring of said disc to move said disc into locking engagement with the lock-slot in the lock bolt.

50 3. In a keyless combination lock, for vehicles and doors, having a lock-bolt provided with a locking slot; a spring-operated disc with a series of teeth along its circumference; and having a series of holes adjacent to said teeth; a pin that may be inserted into any one of these holes; a fixed abutment for said pin to engage and limit the return movement of the disc to normal position; said disc having an opening in 55 which said bolt may be moved; a dog to hold said disc in position; a distance-holder to hold said dog free of the teeth of the disc, when the bolt is in locked position; a manually operated member having an actuating 60 pawl to move the disc, and a beveled edge 65

to cause the space-holding member to release the dog and allow it to engage the teeth of the disc; a finger-like member to operate the dog holding the disc, to force the dog from the tooth engaged and permit the distance-holder to spring into engagement with the dog, and permit the disc to reverse its motion, move into the locking-slot, and secure the bolt from longitudinal movement. 70 75

4. A keyless combination lock, for vehicles and doors, having a lock-bolt; a rotatable disc; a spring tending to restore it to normal position; said disc having a series of teeth along the greater part of its circumference, and a lock-slot in which the lock-bolt may be reciprocated; said lock-bolt having a lock-slot in which said disc may be moved to hold the bolt in locked position; manually operated means to operate said disc; a dog to hold the disc in operative position; a finger-like member to operate the dog holding the disc; a distance-holder; a cam freely mounted on the free end-portion of the bolt; a pulling and twisting member operatively secured to said cam to operate the finger member when the bolt is in locked position, to cause the dog to release the disc and permit the distance-holder to engage the dog and allow the disc to return to normal position, thereby engaging the lock-slot in the bolt and securely preventing any longitudinal movement of the bolt. 80 85 90 95

5. A keyless combination lock, for vehicles and doors, having an openable and closable housing to enclose said combination lock; a snap-lock within said housing to lock the housing when closed; a lock-bolt; a rotatable disc; a spring tending to restore it to 100 normal position; said disc having a series of teeth along the greater part of its circumference, and a lock-slot in which the lock-bolt may be reciprocated; and said lock-bolt having a lock-slot in which said disc may be moved to hold the bolt in locked position; manually operated means to operate said disc; a dog to hold the disc in operative position; a finger-like member to operate the dog holding the disc; a distance-holder; a double cam freely mounted on the free end-portion of the bolt; a pulling and twisting member outside said housing and operatively secured to said cam; one of said cams to unlock the snap-lock in the housing when the bolt is in unlocked position; and the other, when the bolt is in unlocked position, to operate the finger-like member to cause the dog to release the disc and permit the distance-holder to engage the dog and allow the disc to return to normal position, and thereby engage the lock-slot in the bolt and securely prevent any longitudinal movement of the bolt. 105 110 115 120 125

6. A keyless combination lock, for ve- 130

hicles and doors, having an openable and closable housing to enclose said combination lock; a snap lock within the housing to lock the housing when closed; a lock bolt; a rotatable disc; a spring tending to restore it to normal position; said disc having a series of teeth along the greater part of its circumference, and a lock slot in which the bolt may be reciprocated; and said lock bolt

10 having a lock slot in which said disc may be moved to hold the bolt in locked position; manually operated means to operate said disc; a spring device to engage and to hold the disc in operative position; mechanism to release said device to engage and hold said disc in operative position; means to move and hold said device out of engagement with said disc and permit the disc to return to normal position; a cam member

freely mounted on the free end portion of 20 the bolt, a pulling and twisting member outside of the housing and operatively secured to said cam member, whereby, when pulled outwardly and twisted in one direction, said cam member will operate and unlock the snap-lock in the housing when the bolt is in unlocked position; and when twisted in the other direction when the bolt is in locked position, will operate said release mechanism and cause said device to release said disc and thereby permit the disc to engage the lock slot in the bolt and securely prevent any longitudinal unlocking movement of the lock bolt.

25 In testimony whereof I hereunto affix my 30 35 signature,

HENRY N. CARRAGHER.
